SAFETY CAP FOR PREVENTING UNINTENTIONAL FIRING IN GASOLINE POWERED LAWN MOWERS AND THE LIKE

Robert F. Herrling, 1111 S. Ridge Road, Lake Forest, Ill.

Filed May 20, 1964, Ser. No. 80,086

Term of patent 14 years

(Cl. D40—1)

FIG. 1

FIG. 2

FIG. 1 is a perspective view of a safety cap for preventing unintentional firing in gasoline powered lawn mowers and the like, showing my new design;

FIG. 2 is a top plan view thereof, with the safety cap in an alternate position.

I claim:

The ornamental design for a safety cap for preventing unintentional firing in gasoline powered lawn mowers and the like, substantially as shown and described.
